US00D938848S

(12) **United States Design Patent** (10) Patent No.: **US D938,848 S**
(45) Date of Patent: **** Dec. 21, 2021**

(54) **OSCILLATING WEIGHT**

(71) Applicant: **LVMH SWISS MANUFACTURES SA**, La-Chaux-de-Fonds (CH)
(72) Inventor: **Guy Bove**, Geneva (CH)
(**) Term: **15 Years**
(21) Appl. No.: **35/510,132**

(22) Filed: **Mar. 24, 2020**

(80) **Hague Agreement Data**

Int. Filing Date: **Mar. 24, 2020**
Int. Reg. No.: **DM/209755**
Int. Reg. Date: **Mar. 24, 2020**
Int. Reg. Pub. Date: **Aug. 21, 2020**

(30) **Foreign Application Priority Data**

Dec. 26, 2019 (WO) IBDM/205838
(51) LOC (13) Cl. **10-07**
(52) U.S. Cl. ..... USPC **D10/129**
(58) **Field of Classification Search**
USPC D10/128-130
CPC G04B 11/008; B29C 45/1657
